UNITED STATES PATENT OFFICE.

GEORGE F. RICH, OF KANSAS CITY, MISSOURI, ASSIGNOR OF ONE-HALF TO WALLA LEVISTON, OF KANSAS CITY, MISSOURI.

SAFETY-RAZOR.

1,059,487.

Specification of Letters Patent. Patented Apr. 22, 1913.

Application filed December 9, 1911. Serial No. 664,796.

To all whom it may concern:

Be it known that I, GEORGE F. RICH, a citizen of the United States, residing at Kansas City, in the county of Jackson and State of Missouri, have invented certain new and useful Improvements in Safety-Razors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to safety razors and has for its object to provide a device of that type which can be adjusted to different angles, and further in the novel arrangement of parts whereby the blade is held rigidly within a frame and adapted to produce a diagonal stroke with a straight down pull of the razor handle.

It is a further object of my invention to provide other improved details of structure 25 hereinafter described and illustrated in the accompanying drawings, wherein:

Figure I is a perspective view of a safety razor constructed according to my invention, showing the razor disposed at an angle to the handle. Fig. II is a perspective view of the base member, showing the spring members and lock bolt arranged on said base member. Fig. III is a perspective view of the guard member showing a plurality of tooth-shaped guards and the lug member. Fig. IV is a perspective view of the base member with the blade inserted in position. Fig. V is a central vertical section of my safety razor with the different parts in assembled position, and showing the means for holding the razor proper at any desired angle to the handle.

Referring more in detail to the parts: 1 designates a base member which is preferably stamped out of sheet metal and formed with upwardly turned flanges 2, a rearwardly extended lip 3, and a beveled under face 1'. Shoulders 4 are disposed between the lip member 3 and the end flanges 50 2 and are adapted to receive the spring members 5, which are secured to the under face of the said base member 1, and bent over and outwardly away from said lip member. The said flanges 2 adjacent their rear portions 55 are of greater altitude than at their front

portions. The flanges, near their front portions, are provided with upward and rearwardly extending lugs 6, forming U-shaped shoulders 7. The lip member 3, of the base, is provided with a recess 8, adapted to pivotally seat the bolt 9, which is screw threaded and adapted for a thumb screw 10.

The guard member 11 comprises an integral piece of sheet metal provided on its lower front edge with a plurality of tooth shaped lugs 12 and on its lower side edges with oppositely disposed lugs 13. The guard member 11 is concaved as at 14 adjacent the lower front edge, and extends laterally and is convexed as at 15, at which point it is cut away to form the shoulders 16 and extends rearwardly to form the lip 17, having a slot 18 at its free edge the shape of the said curved portions of the guard member conforming to the shape of a razor blade. 75 Rising from the upper edge of the guard member 14 is a stud 19 having an annular groove 22 near its upper end which forms a head 21.

The handle 23 has a collar 24 projecting from one end thereof and has a screw threaded shank 25 projecting through a part of the collar and from an open end thereof, the free end of the shank being preferably reduced in diameter to form a locking pin as will presently be described. The handle also comprises a sleeve 26 which is adapted for telescoping within the collar 24 and has a head 27 provided with an opening which is adapted for receiving the head of stud 19 90 when applied thereto, the sleeve being provided with a base 28 which communicates with the opening and is interiorly screw threaded to carry the screw threaded handle shank 25 so that when the parts are assembled, and the handle is turned to the right, the shank threads will turn in the collar threads and draw the stud toward the handle until the bearing pin binds against the base of the stud groove to hold the parts rigidly 95 together and the handle at a desired angle to the razor blade.

When assembling the razor, the blade is inserted into the base member 1 and is held therein by the lower ends of the springs 5, 105 the upper portion of the springs pressing down upon the upper face of the blade and seating same firmly within the base member. The guard member is then placed on the base member, the lugs 13 seating in the U-shaped 110

shoulders 7 and the spring members 5 of the base member fit into the shoulders 16 of the guard member. The screw threaded bolt 9 of the base member is then swung around 5 until it enters the slot 18 and the thumb screw 10 is turned to draw the lip members of the base and guard together and lock all of the parts against individual movement. When the razor is to be set at an angle the 10 handle is turned to release the screw shank 25 from engagement with the grooved portion of the stud 19 and the handle turned to any desired angle, after which the handle is turned to advance the shank into the stud 15 groove and into binding engagement with the stud.

It is apparent that with a razor of this construction the handle may be set at any angle to a central cross-section of the blade 20 to secure a desirable cutting angle, and that the adjustment may be quickly and easily made without removing the handle or disconnecting the blade holders.

Having thus described my invention, what 25 I claim as new therein and desire to secure by Letters Patent, is:—

1. The combination with blade holding parts comprising a stud having an annular groove therein, of a handle comprising a 30 sleeve having a head at one end into which said stud is projected, and a movable member having a shank projected into the groove in said stud and adapted for locking the handle thereon, for the purpose set forth.

2. The combination with blade holding parts comprising a stud, of a handle comprising an interiorly threaded sleeve having a head at one end into which said stud is projected, and a body member having a 40 collar telescoping over said sleeve, and having a shank in threaded connection with the sleeve, and adapted for binding against said stud, substantially as set forth.

3. The combination with blade holding 45 parts, comprising a stud, of a handle comprising a collar, and a threaded shank projecting through and beyond the collar, a sleeve having threaded connection with said shank and telescoping within the collar, said 50 sleeve having an opening therein into which said stud is projected whereby the handle is rotably mounted on the stud and the shank adapted for binding engagement therewith to lock the parts in adjusted position.

55 4. The combination with blade holding parts comprising a stud having an annular groove at its free end, of a handle having a collar projecting from one end and a threaded shank projecting centrally through the collar, and beyond the end thereof, an interiorly 60 threaded sleeve carried by the shank and adapted for telescoping within the collar, said sleeve having an opening in its end within which the stud is adapted to revolve, 65 whereby said shank may be projected into

binding engagement with the base of said annular groove to lock the parts in adjusted relation, substantially as set forth.

5. In a safety razor, the combination with a blade, of a base member, having flanges on its opposite ends and having springs and a lip at its rear side, said flanges having shoulders near their forward ends, a guard member adapted to seat on said blade, and having lugs for seating in the flange shoulders, and a screw bolt pivotally mounted in said lip and adapted for engaging said guard member to hold the parts together. 70

6. In a safety razor, the combination with a base comprising end flanges having downwardly and forwardly inclined upper edges, and having shoulders at their forward ends, said base having a rearwardly projecting lip, and having upwardly and forwardly curved springs fixed to its rear edge between the lip and the end flanges, a blade mounted on the base, a guard member lying over said blade and having cut-out portions near its rear edge, and lugs at its forward ends projecting into the shoulders on said base flanges, springs on the rear shoulders of the base projecting upwardly and forwardly through the cut-out portions of said guard, and bearing against said guard to yieldingly retain the blade in place, a slotted lip on the rear edge of said guard, and a bolt pivotally connected with the base lip and adapted for projection into the guard lip, a stud on the guard member having a peripheral groove formed thereon, and a handle having a threaded shank adapted for projection into the peripheral groove and for engagement with said stud whereby the handle is adapted for complete revolution around said stud and for adjustment at an angle thereon. 100

7. In a safety razor, the combination with a base comprising end flanges having downwardly and forwardly inclined upper edges and having shoulders at their forward ends, said base having a rearwardly projecting lip, and having upwardly and forwardly curved springs fixed to its rear edge between the lip and the end flanges, a blade mounted on the base, a guard member lying over said blade and having cut-out portions near its rear edge and lugs at its forward ends projecting into the shoulders on said base flanges, springs on the rear shoulders of the base projecting upwardly and forwardly through the cut-out portions of said guard, and bearing against said guard to yieldingly retain the blade in place, a slotted lip on the rear edge of said guard, and a bolt pivotally connected with the base lip and adapted for projection into the guard lip whereby the parts are held together, substantially as set forth. 110

8. In a safety razor, the combination with a base member, having end flanges provided with upwardly and rearwardly facing shoul- 130

ders, and having upwardly and forwardly directed springs at its rear edge, a blade adapted to seat on said base beneath the springs, a guard member having lugs adapted to seat in said shoulders, having cut-out portions at its end through which said springs are projected to bear against the outer surface of said member, and having a slot at its rear edge, a bolt pivotally mounted at the rear of the base member, adapted for movement into the guard slot, and a nut on said bolt adapted to bind against the guard member and hold the parts together.

In testimony whereof I affix my signature in presence of two witnesses.

GEORGE F. RICH.
